Geo. St. Parmele, Esq.
His ATTORNEY.

UNITED STATES PATENT OFFICE.

CHARLES H. KRAUSS, OF JOHNSTOWN, PENNSYLVANIA, ASSIGNOR TO THE LORAIN STEEL COMPANY, A CORPORATION OF PENNSYLVANIA.

RAILWAY-TRACK STRUCTURE.

SPECIFICATION forming part of Letters Patent No. 694,162, dated February 25, 1902.

Application filed August 3, 1901. Serial No. 70,764. (No model.)

To all whom it may concern:

Be it known that I, CHARLES H. KRAUSS, of Johnstown, in the county of Cambria and State of Pennsylvania, have invented a new and useful Improvement in Railway-Track Structures, of which the following is a full, clear, and exact description, reference being had to the accompanying drawings, which form a part of this specification.

10 My invention has relation to certain new and useful improvements in railway-track structures, and more specifically to the structures of that type known as "tongue-switches." Heretofore in the manufacture of 15 tongue-switches for use in connection with T-rail-track work it has been customary to make the foundation structure of the switch of cast metal, either iron or steel, cast from a pattern. To properly connect said structure to the adjacent track-rails, requires the use of "combination-joints" or specially-constructed splice-bars for the reason that the rail members of the casting do not conform accurately in section to the section of the adjacent rails, this being due to the inequalities or warping of the casting or to the fact that it is not practical to make the casting of the same depth of section as the adjacent rails. 20 The making of these combination-joints and special splice-bars to accurately fit the parts to be joined requires considerable backsmithing and handwork, which is slow and expensive.

The object of my invention is to provide a 25 construction of tongue-switch adapted for use in T-rail trackage which can be readily made so as to be capable of connection in the track by means of ordinary fish-plates or splice-bars; also, to provide a construction 30 in which the parts can be readily constructed and assembled and which will be rigid and durable.

With these objects in view my invention consists in the novel construction, combination, and arrangement of parts, all as hereinafter described, and pointed out in the appended claims, reference being had to the accompanying drawings, in which—

Figure 1 is a plan view of a tongue-switch 45 embodying my invention; and Figs. 2, 3, 4, and 5 are transverse sections taken, respec-

tively, on the lines 2 2, 3 3, 4 4, and 5 5 of Fig. 1.

In the figures, A A' designate the main rail members of the structure; B, the branch 55 track-rail; C, a guard-rail, and D the pivoted tongue.

E is a body of cast metal which unites and secures the rail members A, B, and C, and F is a cast filler fitted between the rail members 60 C and D and forming a bed or support for the switch-tongue D.

The structure is mounted and assembled in the following manner: The rail members A, B, and C, which are lengths of ordinary 65 T-rail, are placed in a suitable mold and the metal body E is cast about them, being cored to form a pocket in which is seated a plate G of harder material, which forms the seat for the point of the tongue, for the purpose 70 of providing this part of the structure with increased wearing qualities. The filler F is cast from a suitable pattern, the T-rail A' being placed in the mold and having its end cast in the said body, as shown. The mold 75 is also provided with cores which form a series of transverse bolt-seating apertures in the piece. It is also provided with a core adapted to seat a piece of guard-plate I. This cast filler-piece is inserted between the 80 rail members B and C and is secured thereto by a series of bolts K, which pass through the said apertures. The guard-section I may be readily cast in place, if desired; but it is 85 preferably seated in the core after the parts are assembled, for the reason that a piece of any desired length can then be used.

L is a short piece of guard-section which is cast in the body E.

The rail members A A' and B can be of the 90 same section as the rails of the adjacent tracks, to which they can be secured by means of the ordinary joints. The construction as a whole results in a very solid and durable structure.

Having thus described my invention, what 95 I claim, and desire to secure by Letters Patent, is—

1. A tongue-switch structure, consisting of two separate cast-metal bodies in which rail members of the structure are held, one of said 100 bodies being secured to and between rail members of the other body.

2. In a tongue-switch structure composed of two parts, one of which consists of a cast-metal body forming a seat for the heel portion of the switch-tongue, and of a main rail member to which the said body is cast, and the other part consisting of a cast-metal body having a seat for the point end of the switch-tongue, and of main, branch and guard-rail members to which said body is cast, together with bolts which secure said parts together.

3. The herein-described tongue-switch structure, comprising main and branch rail members consisting of T-rail corresponding in section to that of the adjacent rails, a guard-rail member, a cast-metal body cast about the adjacent ends of said rail member, a cast filler secured between said branch and guard-rail members and forming a bed for the switch-tongue, and a main rail member secured to said filler.

4. A tongue-switch structure having one of its main rail members, its branch rail member, and a guard-rail member united by a body of metal cast about the end portions thereof, a second cast-metal body fitting between and secured to the branch rail mem-

ber and the guard-rail member and forming a support for the switch-tongue, and a second main rail member having its end portion cast into the last-named body.

5. In a tongue-switch structure of the character described, the combination with the T-rail members A, B and C and the pocketed cast-metal body E, of the filler F fitting between the members B and C and forming a bed for the switch-tongue, and the T-rail member A' secured to said filler.

6. In a tongue-switch structure of the character described, the combination with the T-rail members A, B and C and the pocketed cast-metal body E of the filler F fitting between the members B and C and forming a bed for the switch-tongue, and the T-rail member A' secured in said filler, said filler also seating a guard-section for the rail member B.

In testimony whereof I have affixed my signature in presence of two witnesses.

CHARLES H. KRAUSS.
